STORE CONSTRUCTION

Rosario Lo Magro, Philadelphia, Pa.

Application July 25, 1938, Serial No. 221,129

1 Claim. (Cl. 20—1.6)

My invention relates to a new and useful store construction and it relates more particularly to the construction of a store used for dispensing odorous merchandise such as live poultry, fish and the like. As constructed today, stores of this character are obnoxious to the neighborhood in general and to the purchasing public in particular since the customer has to make a purchase in an enclosure permeated with foul odors such as the body smells and droppings of poultry or the smell of fish or the like.

It is therefore the object of my invention to produce a novel store construction by means of which the purchasing public is completely excluded from contact with the part of the store in which the live poultry or the like is displayed, and by means of which a purchase may be consummated between the attendant and the customer without any discomfort or inconvenience to the customer.

To that end my invention consists in segregating this portion of the store and forming it into a clean compartment free of all odors, and also consists in providing means for exchange of information, money and merchandise without admitting any of the odors from the working part of the store to the customers' compartment or waiting room.

My invention will be more clearly understood from the following specification and the accompanying drawings in which:

Fig. 1 represents a diagrammatic plan view of a store construction embodying my invention.

Fig. 2 represents, on an enlarged scale, a horizontal section through a speaking tube arrangement for establishing communication between the customer and the attendant.

Fig. 3 represents a section, on an enlarged scale, on line 3—3 of Fig. 1.

Fig. 4 represents a section on line 4—4 of Fig. 3.

Fig. 5 represents a fragmentary sectional view on line 5—5 of Fig. 1.

Referring to the drawings in which like reference characters indicate like parts, a store embodying my invention will consist of a stock room 1 having the crates 2 containing the live poultry or other merchandise, and a slaughter or cleaning room 3 which communicates through the door 4. 5 designates the customers' compartment or waiting room which is separated from the stock room 1 by the glass partitions 6 which preferably extend from the floor to the ceiling. The compartment 5 is provided with any suitable door or doors 7 leading to the street, and it is also provided with a sliding door 8 which, through the

sliding door 9, leads to the compartment 1. The door 8 also leads to the customers' compartment 10 which is also separated from the stock room 1 by the glass partition 6. The use of the sliding doors 8 and 9 permits communication between the compartments 1, 5 and 10 while, at the same time, minimizing the travel of odors from the compartment 1 to the compartments 5 or 10. The compartment 10 may also have a street door 11. In order to establish communication between the attendant in the compartment 1 and the customers in the compartment 5 I provide a form of speaking tube arrangement best shown in Fig. 2, which consists of a pair of ear pieces 12 and 13 extending to one side of the glass partition 6 and another pair of ear pieces 14 and 15 extending to the other side of the glass partition 6. The speaking tube arrangement also includes the oppositely disposed horns or mouth pieces 16 and 17 which are provided with the holes 18 for venting the breath of a person speaking into either of the mouth pieces 16 or 17. The speaking tube arrangement is positioned above the floor at about the average height of a person and, inasmuch as several speaking tube arrangements are used, it is possible to arrange some of them at a higher and some of them at a lower level to render them accessible to persons of different heights. The customer and attendant exchange information through the speaking tube arrangement and, if the attendant speaks into the mouth piece 16, for instance, the customer hears what he has to say through the ear pieces 14 and 15, and when the customer talks into the mouth piece 17 the attendant hears through the ear pieces 12 and 13, the ear pieces extending beyond the ends of the mouth pieces 16 and 17 and being so spaced as to be adjacent to the ears of a person speaking into either of the mouth pieces.

In order to enable the customer to pay the price and to get his receipt I provide the construction best seen in Figs. 3 and 4 which comprises a stationary box formed of the wall 21 and the bottom 22 and which is fitted into the glass partition 6, and a sliding box formed of the walls 21x and 22x, it being noted that normally the top 22x abuts against the bottom edge of the upper portion of the glass partition 6 by means of the spring 23. 24 designates guides along which the sliding box is adapted to travel. When the customer desires to insert his hand into the compartment 1, the top 22x is depressed, and when the hand is withdrawn the spring 23 automatically closes the opening. After the chicken, or other merchandise, has been purchased, the at-

tendant passes it through the door 4 into the slaughter or cleaning room 3, and after it has been prepared by the attendant and wrapped the attendant drops it into the chute 25. The chute 5 25 is provided with a door 26 which, by gravity, normally closes the end of the chute leading to the compartment 5. The packaged merchandise drops, by gravity, through the inclined chute 25 onto the basket or platform 27. At this point an 10 attendant hands the purchase to the customer in exchange for his receipt. 28 designates a rest room provided with washrooms 29 and accessible to the compartment 5 through a conventional door 30 and a sliding door 31. 32 designates steps 15 leading down into the cellar.

With reference to the partition 6 which divides the waiting compartments 5 and 10 from the stock or attendants' compartment 1 and the cleaning room 3, it is within the scope of my invention to build the lower portion of this partition, say, about "belt high" of the average person, of masonry such as bricks or tiles, or of wood-work or the like, and to extend the transparent part of the partition from there to the ceiling. 25 Also, the money and receipt exchange sliding box construction shown in Fig. 3 is preferably fitted into the solid lower portion of the partition. This not only gives a better appearance, but also strengthens the construction. Also, the 30 box shown in Fig. 3, for the purpose of exchange of the money and the receipt, etc., can, if desired, be provided on the side thereof towards the compartment 1 with any desired conventional latch or lock to lock it against unauthorized use when the attendant is absent.

The speaking tube arrangement best seen in Fig. 2 is only shown diagrammatically by way of illustration and I am not limited to the exact construction since any other means which permits 40 communication through the partition 6 such as a microphone or other sound-amplifying equipment may be used at will.

In the present instance, the ear pieces 12, 13, 45 14 and 15 are adapted to transmit sound from the central diaphragm 31 which is interposed between the mouth pieces 16 and 17.

Where the construction shown and described is

used in a live poultry store, for which it is primarily intended, the segregation of the customers in the compartment 5 from the compartment 1, not only protects the customers from the foul odors which are ever present, but also against the dust which is stirred up by the movement of the chickens and by their scratching. Also, it frequently happens that a chicken flies loose while the attendant is trying to extricate it or another chicken from the coops or crates 2 thus causing considerable dust and disturbance, and also it has been known to cause injury to customers as by the chicken flying in the face of a customer, or as by scaring women and children and thus indirectly causing accidents which result in inconvenience, discomfort and sometimes 10 15 in injury.

It will thus be seen that according to my novel store construction the customers in the compartments 5 or 10 are completely protected from the 20 odors of the live poultry or the like, and that an efficient expeditious means is provided for exchange of information, for the payment of the price and for delivery of the goods in a pleasant and sanitary manner.

Having thus described my invention, what I 25 claim as new and desire to secure by Letters Patent is:

The combination with a store construction having a compartment for the use of attendants, a compartment for the use of customers, a substantially air-tight transparent partition separating said compartments and having an opening formed therein, and means carried by said partition for transmitting oral communication between attendants and customers, of means for 30 exchange of commodities through said opening in said partition comprising a lower boxlike member, an upper inverted boxlike member telescopically sliding within said lower member and a spring for normally retaining said upper boxlike member in its uppermost position, said lower boxlike member and said upper boxlike member, when the latter is in its uppermost position, completely closing the opening in said partition.

ROSARIO LO MAGRO.
